UNITED STATES PATENT OFFICE.

WALTER A. BOWE, OF TIFFIN, OHIO, ASSIGNOR OF ONE-HALF TO GEORGE W. MIK, OF TIFFIN, OHIO.

WATER-CLOSET.

1,276,965.

Specification of Letters Patent. Patented Aug. 27, 1918.

Application filed October 8, 1917, Serial No. 195,210. Renewed July 15, 1918. Serial No. 245,070.

To all whom it may concern:

Be it known that I, WALTER A. ROWE, a citizen of the United States of America, and resident of Tiffin, county of Seneca and State of Ohio, have invented certain new and useful Improvements in Water-Closets, of which the following is a specification.

This invention relates broadly to water closets, and it has for its primary object to provide a closet which embodies therein means for exhausting gases and odors therefrom during the operation of flushing.

A further object is to provide a relatively simple and inexpensive mechanism for removing gases and odors from a water closet, such mechanism being located wholly within the closet and being actuated by a diverted portion of the water employed for accomplishing the flushing of the bowl.

With these and other objects in view, the invention resides in the features of construction, arrangement of parts and combinations of elements which will hereinafter be fully described, reference being had to the accompanying drawings, in which—

Figure 1 is a partial sectional view of a closet bowl embodying my invention;

Fig. 2 is a front edge view of the seat, detached; and

Figs. 3, 4 and 5 are views of the same in top plan, rear edge elevation and side elevation, respectively.

Referring to said drawings, in which like designating characters distinguish like parts throughout the several views—

1 indicates the body portion of the bowl of a water closet, which portion may be of any usual or preferred type or form, the bowl herein depicted for illustrative purposes being of that type in which the water for flushing is supplied to a hollow perforated roll-like rim 2 from a flush tank (not shown) which connects to an upright tubular intake member 3 formed integral with said bowl.

Formed integral with the upper part of the bowl and extending rearward therefrom is a tubular vent portion 4 adapted to have a vent pipe attached thereto. Rotatably mounted within the vent tube 4 is a fan 5 designed, when actuated, to produce a suction which will exhaust foul air, gases, odors, and the like from the bowl and direct the same outward to the atmosphere through the usual vent pipe above mentioned. Said fan is fixed upon a horizontal shaft 6 which is

disposed longitudinally within the vent tube 4 and which has its ends suitably mounted for rotation. As depicted, one end of said shaft is disposed in a socket 7 provided in the lower end of a depending arm 8 carried by or formed integral with the closet bowl, and the other end is disposed in a recess 9 provided in the upper end of an upright post 10 located within said vent tube. As is obvious, either or both the arm 8 and post 10 may be formed integral with the bowl, or either or both may consist of a metal post detachably mounted in the manner in which said post 10 is herein illustrated.

The said supports for the shaft 6 are so located that a portion of said shaft lies underneath the base 11 of the intake member 3, which base has a hollow tapered funnel-like member 12 depending therefrom through which some of the incoming flush water supplied to the bowl through the intake 3 is diverted. Fixed upon said shaft in a position to receive the impact of the water entering through the passage 13 in said funnel-like member 12 is a bladed propeller or water wheel 14.

As is obvious, when water is admitted in the usual manner for flushing the bowl, a portion thereof is directed through the passage 13 against the blades of said water wheel 14, producing rapid rotation of the shaft 6 and fan 5.

To facilitate the removal of the gases and odors, provision is preferably made for admitting fresh air to the bowl as the foul air is withdrawn by means of the fan. While any appropriate passage may be provided in the seat 15 for admitting fresh air when the usual lid or cover 16 occupies its lowered position, I prefer to form the substantially rectangular recess 17 in the under side of the front end of the seat which is shown in Figs. 2, 3 and 5, so that when said seat occupies a seated position upon the bowl, a passage is constituted between said seat and said bowl.

The rear end of the seat has a recess or notch, as 18, formed therein to fit about the adjacent portion of the bowl when said seat is lowered upon the latter.

What is claimed is—

1. The combination with a closet bowl having a vent tube, of a rotary shaft disposed longitudinally within said tube, a fan carried by said shaft, a propeller carried by said shaft, and means for directing a portion

of the water used in flushing said bowl into operative relation to said propeller, said means being functional only during the operation of flushing the bowl.

5. The combination with a closet bowl having a vent tube, of a rotary shaft disposed longitudinally within said tube, a fan carried by said shaft, and means whereby water admitted for bowl flushing purposes 10 actuates rotation of said shaft, said means being inactive except during the operation of flushing the bowl.

3. The combination with a closet bowl having a vent tube, of a rotary shaft disposed longitudinally within said tube, a fan carried by said shaft, means for diverting some of the water admitted for bowl flushing purposes to said tube, and means in the path of and actuated by the diverted water where- 20 by said shaft is rotated during the bowl-flushing operation only.

4. The combination with a closet bowl having a flush-water intake and a vent tube, of a rotary shaft disposed within said tube, 25 a fan carried by said shaft, a water wheel carried by said shaft, and means for directing some of the flush water admitted through said intake into engagement with said wheel for rotating said shaft, said means being functional only during the operation of flushing the bowl.

5. The combination with a closet bowl having a flush-water intake and a vent tube, of a rotary shaft disposed within said tube, 35 a fan carried by said shaft, a water wheel carried by said shaft, and means affording a passage through which a portion of the water entering the bowl through said intake for bowl-flushing purposes is diverted into propelling engagement with said wheel, said means being incapable of functioning except during the bowl-flushing operation.

6. The combination with a closet bowl having a flush-water intake and a vent tube, 45 of a pair of supports located within said tube, a shaft having its ends mounted in said supports, a water wheel carried by said shaft, a communicating opening between said intake and said tube affording a passage 50 through which some of the water entering the bowl through said intake as for bowl-flushing purposes is diverted into propelling engagement with said wheel for rotating said shaft, and a fan fixed upon said shaft.

55. 7. The combination with a closet bowl having a flush-water intake and a vent tube, of a pair of supports located within said tube, a shaft having its ends mounted in said supports, a water wheel carried by said shaft, a funnel-like member opening into 60 said intake and depending within said tube into close proximity to said wheel for diverting and directing some of the water ad-

mitted through said intake for bowl-flushing purposes into propelling engagement with 65 the wheel for rotating said shaft, and a fan carried by said shaft.

8. A ventilating water closet comprising a closet bowl having an integral rearwardly directed tubular vent at the upper part 70 thereof and having a flush-water intake disposed directly over the forward end of said vent, a rotary shaft disposed longitudinally within said vent, a water wheel carried by said shaft, a funnel-like member opening 75 through the upper wall of said vent and depending within said vent to closely overlying proximity to said wheel, said member being located in alinement with said intake and being adapted to divert some of the 80 water admitted through the latter in flushing the bowl into propelling engagement with the wheel for rotating said shaft, and a fan carried by said shaft.

9. A ventilating water closet comprising 85 a closet bowl having an integral rearwardly directed tubular vent at the upper part thereof and having a flush-water intake disposed directly over the forward end of said vent, a rotary shaft disposed longitudinally 90 within said vent, a water wheel carried by said shaft, a fan carried by said shaft rearward of said water wheel, and a passage through which some of the water admitted through the intake for flushing the bowl is 95 diverted into said vent, said passage having its receiving end located in line with the direction of flow of the water entering through said intake and having its discharge end located in operative proximity to said 100 wheel.

10. A ventilating water closet comprising a closet bowl having an integral rearwardly directed tubular vent at the upper rear part 105 thereof and having a vertically disposed flush-water intake disposed directly over the forward end of said vent, said intake having a portion of the upper wall of said vent as a base and having a side-opening passage through which water is admitted to the bowl 110 for flushing purposes, a rotary shaft disposed longitudinally within said vent, a water wheel carried by said shaft beneath the intake base, said base having an opening therein through which some of the flush 115 water admitted through said intake is directed into propelling relation to said wheel, and a fan carried by said shaft rearward of said wheel.

In testimony whereof, I affix my signature in presence of two subscribing witnesses.

WALTER A. ROWE.
